UNITED STATES PATENT OFFICE.

IGNAZIO GATTI, OF NEW YORK, N. Y.

JEWEL-SETTING TOOL.

Application filed March 15, 1923. Serial No. 625,374.

To all whom it may concern:

Be it known that I, IGNATIUS GATTI, a subject of the King of Italy, residing at New York, in the county of New York and State 5 of New York, have invented certain new and useful Improvements in Jewel-Setting Tools, of which the following is a specification.

This invention relates to jewel setting 10 tools and more particularly to a novel and improved flange crimping plier, particularly adapted for setting jewels or gems in rings, bar pins and other kinds of jewelry.

One of the objects of my invention is the 15 provision of a jewel setting tool especially designed for gripping the flanges of a ring, bar pin or other piece of jewelry in such manner as to engage a natural or artificial gem including provision for limiting the 20 pressure to be applied during the crimping operation thus permitting the setting of gems with rapidity and with great efficiency.

Another object of my invention is the 25 provision of a jewel fitting tool in the form of a pair of pliers having an anvil head and a crimping head cooperating with each other to engage the metal of the particular piece of jewelry in which the stones are to be set.

In order to more fully understand my invention, reference is had to the accompanying drawings showing a preferred embodiment thereof, wherein,

Figure 1 is a side view showing the application 30 of my invention,

Figure 2 is a bottom plan,

Figure 3 is an end view of the crimping 35 and anvil head,

Figure 4 is a sectional view showing the 40 crimping head and its relation to the setting, and

Figure 5 is a section of a detail or modified form of an anvil head for use on straight 45 work.

Referring now to the drawings, wherein like reference characters designate corresponding parts throughout the several views, 50 5 designates the upper handle and 6 the lower handle of the tool. The upper handle 5 is preferably formed integral with the slotted body 7 being provided at its extreme forward end with an anvil head 9, the top face of which is curved as indicated at 10 for a purpose presently to appear. The lower 55 handle 6 is preferably formed integral with the body portion 11, being pivoted as indi-

cated at 12 and terminating in a crimping head 13 for cooperating with the anvil head 10 above referred to.

The lower face of the crimping head is 60 provided with a curved, inverted, V-shaped groove 14, it being observed that the curve of said groove extends from the opposite side 15 of the crimping head 13, more clearly shown by Figure 3 of the drawings. The 65 handle 6 is provided with a vertically extending stud 17 and the handle 5 with an adjusting screw 18 and lock nut 19 whereby the tool may be set to the proper position 70 for affecting the crimping of the metal when setting the stones.

The tool above described is particularly adapted for use in setting stones and gems in rings, having the side flanges 20, 21, between which the gems or stones 22 are temporarily positioned, preliminary to the crimping of the flanges shown more clearly by Figure 4 of the drawings. The ring proper is usually provided with a series of spaced apertures throughout the circumference of the ring and between the flanges, 75 cement or any other adhesive is applied so as to temporarily hold the stones or gems in position. After the tool has been set to the desired degree by the mechanic, pressure 80 is applied to the flanges gradually as the ring is turned on the anvil head 10 thus pressing the metal toward the gem or stone whereby they are crimped very effectively 85 and quickly. The curved portion of the bottom 90 grooved face of the crimping head 13 conforms to the curvature of the face 10 of the anvil head and consequently, it will be seen that the flanges are crimped regularly as the handles are pressed toward each other 95 as is understood. In the form of the invention shown by Figure 5, wherein it is desired to crimp the flanges of a straight piece of metal, the crimping head 13^a and the anvil head 14^a are provided with straight edges 100 at their meeting surfaces to accomplish the same result as above set forth.

While I have illustrated and described my invention with some degree of particularity, I realize that in practice various alterations 105 therein may be made. I therefore reserve the right and privilege of changing the form of the details of construction or otherwise altering the arrangement of the correlated parts without departing from the spirit of 110 the invention or the scope of the appended claim.

Having thus described my invention what I claim as new and desire to secure by United States Letters Patent is:—

A gem setting tool of the class described comprising pivotally connected handles, one of said handles terminating in an anvil head, the top face thereof being gradually curved, the complementary handle terminating in a crimping head of substantially the same 10 length as the anvil head, said crimping head having an inverted V-shaped bottom face

shaped to conform to the curvature of the anvil head and adjustable means between the handles for limiting the pressure of said anvil and crimping heads.

In testimony whereof I affix my signature in presence of two witnesses:

IGNAZIO GATTI.

Witnesses:

ALBERT G. GRADALE,
JOSEPH MANTANI.
